UNITED STATES PATENT OFFICE.

ELHANAN L. MOODIE, OF NEW YORK, N. Y., ASSIGNOR OF ONE-HALF TO
CHARLES H. GILLESPIE, OF SAME PLACE.

DESIGN FOR AN ORNAMENTAL OR ADVERTISING EASEL.

SPECIFICATION forming part of Design No. 12,905, dated April 25, 1882.

Application filed March 4, 1882. Term of patent 3½ years.

To all whom it may concern:

Be it known that I, ELHANAN L. MOODIE, a citizen of the United States, residing in the city and county of New York, in the State of New York, have invented and produced a new and original Design for Ornamental or Advertising Easels, of which the following is a specification, reference being had to the accompanying drawing or photographic representation, forming part thereof, and in which the figure is a front view.

This invention relates to a novel design for the front or plate of an ornamental or advertising easel; and the same consists in a design comprising the pictorial representation of a sunflower, a lily, and a leaf, the representation of each being arranged in substantially the relation with that of the others as shown in the front view of the drawing or photographic representation annexed. Thus, for example, the central and lower portion of the design is occupied by the representation of a sunflower, of which the core or seed portion is represented at A and the radial leaves at B. Extended laterally and upwardly at opposite sides of this representation of a sunflower is the representation of parts of a broad leaf, C, while above the sunflower and between the upper lateral portions of said leaf is the representation of a calla lily. The circumference of the plate or front of the easel aforesaid follows substantially the circumferential contour of the representations of the sunflower, leaf, and lily as the same are joined. Thus, for example, one portion of the circumference of said front or

plate follows substantially the contour of the lower part of the sunflower. Other portions thereof follow substantially the outer contour of the lateral portions of the leaf, while the remaining parts follow substantially the contour of the upward and lateral projecting portions of the calla lily. 40

As a matter of taste, there may be represented upon the surface of one lateral portion of the leaf C the pictorial representation of a fern or vine-like or trailing plant; but this may be omitted without changing the essential features of my said design. 45

It is to be understood that the representation of the sunflower, of the leaf, and of the lily are each in practice to be made in colors the same as, or approximating to, those of the natural flowers. Thus the core of the sunflower of a dark-brown or blackish color and the petals of a yellow, the portions C of the leaf of a green, and the calla lily a white tinted more or less with yellow. 55

What I claim as my invention is—

The design for an ornamental or advertising easel composed of the representations of a sunflower, leaf, and lily arranged in substantially the juxtaposition herein described, and with the circumferential contour of the easel corresponding substantially to the circumferential contour of the joint representations aforesaid, 60 substantially as herein set forth. 65

ELHANAN L. MOODIE.
